UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

CUTTER-GRINDING MACHINE.

1,389,325.

Specification of Letters Patent. Patented Aug. 30, 1921.

Application filed October 21, 1919. Serial No. 332,323.

To all whom it may concern:

Be it known that I, JOHN J. THACHER, a citizen of the United States, residing at Wethersfield, in the county of Hartford and 5 State of Connecticut, have invented certain new and useful Improvements in Cutter-Grinding Machines, of which the following is a specification.

This invention relates to cutter grinding 10 machines and particularly to an improvement on the cutter grinding machine shown in Patent 730,455 granted to Mr. B. M. W. Hanson on June 9th, 1903.

In a grinding machine of the type stated, 15 there is provided a rotatable work support and one or more spindles having grinding wheels thereon adapted to be moved across the work, such work herein being shown as a milling cutter and the grinding wheels 20 being shown as sharpening the same. Mechanism is provided between the drive shaft and the spindles for longitudinally reciprocating the latter across the work in the grinding operation. It is a particular object 25 of this invention to provide an improved mechanism for this purpose which will be more rigid and less susceptible to wear and which will better sustain the main strain and wear of the machine which is required of 30 this reciprocating mechanism.

Certain of the grinding spindles in the present invention are mounted on a support adjustable circumferentially about the machine frame and it is a particular object of 35 the invention to provide improved operating means for reciprocating these spindles in whatever position the spindle supports may be adjusted.

When operating on cutters of relatively 40 small size, the actual working stroke of the grinding spindles is shorter than when working on larger cutters and it is therefore not necessary that the spindles operate at full stroke on such small work. It is accordingly 45 an object of the invention to provide improved means for adjusting the stroke of the spindles to the length desired.

With the above and other objects in view, 50 which will be more fully disclosed as the description of the invention proceeds, the invention more specifically resides in the following structure.

Referring to the drawing:

Figure 1 is a plan view of the improved 55 cutter grinding machine.

Fig. 2 is a part sectional view taken approximately on the line 2—2 of Fig. 1 looking in the direction of the arrow, certain elements being omitted therefrom and other parts being shown in elevation to more 60 clearly disclose the improved structure constituting the invention.

Fig. 3 is a sectional view taken on the line 3—3 of Fig. 2 looking in the direction of the arrow and showing certain parts broken 65 away to more clearly disclose the invention.

Fig. 4 is a detail view showing more clearly the mechanism whereby the length of stroke of the grinding spindles may be varied.

Referring more specifically to the drawing by reference characters wherein like numerals designate like parts in the several views, 1 designates a suitable pedestal serving as a support for the bed plate 2 of the 75 grinding machine and preferably has secured adjacent its upper end a pan 3 for conveniently holding any tools being used by the operator. As in the aforesaid patent, the work spindle support 4 is mounted directly on the bed plate 2 and held thereon by means of screws or otherwise. The work spindle 5 is journaled in this support and adapted to be indexed by a suitable mechanism hereinafter described.

Two grinding spindle supports 6 are mounted on the bed plate 2 and are secured in any position circumferentially thereon by means of clamps 7 extending into the T-slot 8 in the bed plate. As shown most 90 clearly in Fig. 3, a slide 9 forming at its upper end a bearing for the grinding spindle 10 is mounted to slide transversely on each of the supports 6. A third grinding spindle 10' is mounted in a like slide 9' 95 which is adjustably mounted directly on the bed plate 2. A screw 11 is provided as shown for transversely adjusting each of these slides. Each grinding spindle is rotatably and longitudinally slidably mounted 100 in its support and has mounted on the opposite ends thereof an operating pulley 12 and a grinding wheel 13. Each of the three grinding spindles shown in the drawing are identical and from the structure just described it should be clear that two of the spindles may be adjusted in a direction transversely of the spindle itself, that each

spindle is movable longitudinally in operation, and that two of the spindles are cir- 110

cumferentially adjustable on the bed plate. The mechanism thus far specifically described is substantially that shown in the patent referred to above.

5 The improved means for operating the work performing elements of the machine will now be described. As hereinbefore stated, the greatest wear and strain on the machine is in those parts which reciprocate 10 the grinding spindles in their working operation. It is therefore very essential that such mechanism be made very substantial and be of a very rigid and strong character. With this object in view, I have herein 15 shown as one embodiment of my invention a series of members, each of a very substantial character and interengaged in such manner as to positively transmit reciprocatory motion to the said spindles without excessive wear, without danger of breaking such members, and without wasting energy through lost motion or looseness.

As such a means for transmitting reciprocatory motion to the spindles, I prefer to 20 provide a series of lever arms having direct toothed engagement with each other as shown in Figs. 2 and 3. An arm 14 is shown as having direct engagement with a collar 15 on each spindle although it is obvious 25 that the engagement might be with a slide-able carriage in which the spindle is mounted if desired. The lower end of each arm 14 is pivotally mounted on one end of a lever 16 pivoted at 17 and 17', the two pivots 17 30 corresponding to the two circumferentially adjustable spindles being on a bracket 18 secured to the spindle support 6 and the third pivot 17' being on the bed plate 2. Such pivoting of each arm 14 on the lever 35 16 permits the slide 9 to be adjusted trans-versely while still maintaining the arm in operative engagement with the spindle. The other end of each circumferentially adjustable lever has toothed engagement 19 with 40 one arm of a member pivoted at 20 to an ex-tension of the bracket 18. A second arm 21 projecting from the said member has toothed engagement with a circular rack 22. The other arm 16' of the lever 16 on the pivot 17' 45 has toothed engagement 23 with the toothed sector of an arm or lever 24 pivotally mounted on a rock shaft 25 mounted in the ma-chine frame. A second arm or lever 25 is mounted on the other end of this shaft and 50 is provided with a toothed sector for engag-ing the circular rack 22. It is of course ob-vious that other means than the toothed en-gagement described might be employed for transmitting the reciprocatory motion of the 55 rack 22 to the spindles, but the structure shown is particularly preferable since the same is strong and accurate and not likely to get out of order. Also the toothed en-gagement between each arm 21 and the cir-60 65

gagement of these elements is maintained no matter in what circumferential position the spindle supports 6 may be adjusted. It will be noted that there is no necessity for circumferentially adjusting the spindle 10' 70 hence the reason for mounting the operating means therefor directly on the machine frame.

As a means of reciprocating the circular rack 22 from the main drive shaft 27, I dis-close the following mechanism. An eccen-tric pin 28 on the disk 29 secured to the end of the shaft 27 engages in a slot provided in a plate 30 secured to the upper end of a rod 31 (Fig. 4). The circular rack 22 is 80 slidably mounted on this rod and houses a compression spring 32 between the rack and a member 33 secured to the lower end of the rod by means of nuts 34. The spring 32 is sufficiently strong to normally hold the rack 85 up in engagement with the plate 30 in such manner that the rack normally moves with the rod the full stroke of the latter and car-ries the spindles through such stroke.

To shorten the operating stroke of the 90 spindles when desired, I provide means act-ing against the normal action of the spring 32 to limit the upward movement of the rack 22. The herein described means for this purpose is best shown in Figs. 2 and 4. An 95 arm or lug 35 extends outward from the hub of arm 24 on the rock shaft 25 and a screw 36 is adapted to be adjusted into the path of movement of said lug to limit the 100 rocking movement of the rock shaft in one direction. As shown, in Fig. 2, this screw is threadedly mounted in a bracket 37 on the machine frame and may be adjusted through the bracket to any position desired to thereby limit the upward movement of rack 22 105 and the operative stroke of the spindles. By referring to Fig. 2 it will be seen that the rod 31 always operates at the same stroke and that the compression of spring 32 and the sliding of rack 22 on the rod permits the 110 limiting of the upward movement of the rack.

As shown in Fig. 2, I prefer to drive the main drive shaft 27 through a gear 38 and a step pulley 39 on a countershaft 40 mount-ed in a bracket 41, such bracket serving as a belt tightener by the operation of screw 42. Gear 38 meshes with a gear 43 on the drive shaft 27 whereby the drive shaft and the machine are operated.

As heretofore stated, the work spindle 5 is mounted on the support 4 and is adapted to carry on one end thereof a cutter 44 to be sharpened and on the other end a toothed index wheel 45. During the sharpening op-eration it is necessary that the cutter be ro-tated and the mechanism herein shown for performing this operation will now be de-scribed. A hub 46 carrying an arm 47 and a projection 48 is loosely mounted on the 130

spindle 5 and connected with the cam engaging element 49 through the projection 48 and a link 50, a spring 51 surrounding the said hub normally holding the element 49 in engagement with the cam 52 on the main drive shaft 27. A pawl 53 is pivotally mounted on the arm 47 and is adapted to engage the teeth of the index wheel 45 to rotate the spindle and index the work, herein shown 10 as a milling cutter. To provide for varying the amount of indexing given to the spindle 5 on each rotation of the drive shaft 27, I herein show a shield 54 adapted to be moved about the periphery of wheel 45 and in the 15 path of movement of the pawl 53. This shield serves to lift the pawl from the wheel during a portion of its operative stroke if desired, thereby rendering the pawl inoperative at such time.

20 Different index wheels 45 must be used for indexing work of different kinds and size and it is therefore often necessary to remove the wheel 45 and substitute another therefor. In the drawing I show one embodiment of simple means whereby this change 25 may be more readily and conveniently made than heretofore. As shown in Figs. 2 and 3, the wheel 45 slides over the hub 55 and is held thereon by means of a thin threaded plate 56 having wrench engaging facets 57 on its periphery. The opening in this plate and in the index wheel is of such relative size that both may be removed directly from the shaft without removing the wing nut 58 or 30 any of the other parts of the machine.

35 As shown in Figs. 1, 2 and 3, I have provided improved means whereby the machine is kept well lubricated. This construction comprises briefly an oil reservoir 59 having 40 ducts leading therefrom to the main drive shaft and other operating parts. I also provide oil cups for the main bearings as shown in the drawings.

45 From the foregoing description the operation and the material advantages of the improved structure should be obvious. By providing a limited number of rigid and strong parts and by interconnecting such parts in the positive manner shown, an improved machine has been provided which 50 will be more accurate and will better withstand the wear incident thereto without easy breakage of any parts thereof. Also the improved adjustable spindle stroke provided 55 renders the machine very accurate and the arrangement of the parts is very compact and such that the spring 32 is completely housed. The full operative engagement between the levers 21 and the circular rack 22 60 in all circumferential positions of adjustment of the supports 6 is also of material advantage in this machine.

65 Briefly described, the operation of the machine is as follows: Assuming that the work, herein shown as a milling cutter, has been secured to the index spindle 5 as shown in Fig. 1 and that the grinding spindle supports have been adjusted to place the grinding wheels in the proper position relative to the work, the operator turns on the power 70 and the machine operates as follows. The rack 22 is reciprocated from the drive shaft by the mechanism described and by means of the operating mechanism between the rack and the spindles, the said spindles are 75 reciprocated across the work. As shown in Fig. 1, two of the grinding wheels operate on the sides of the teeth of the milling cutter while the third grinding wheel operates on the periphery thereof. At each rotation of 80 the drive shaft 27 the milling cutter is indexed through the desired distance by means of the indexing mechanism heretofore described. Should it be desired to shorten the stroke of the spindles, the operator adjusts 85 screw 36 inwardly against the arm 35 on the rock shaft whereby the rack 22 is prevented from moving its full stroke upwardly and the stroke of the spindles is shortened thereby.

90 What I claim is:

1. A cutter grinding machine comprising the combination of a rotary work support, a plurality of rotatable spindles each adapted to receive a grinding wheel thereon to 95 dress the work, a support for each spindle, means permitting adjustment of each spindle support angularly relative to the work support, a member pivoted to each spindle support and having an arm directly 100 engaging the spindle, and mechanism for operating each member about its pivot to longitudinally reciprocate the spindles.
2. A cutter grinding machine comprising the combination of a bed plate, a rotary work 105 support thereon, a plurality of rotatable spindles each adapted to receive a grinding wheel thereon to dress the work, a support for each spindle, means permitting adjustment of the spindle supports circumferentially around the bed plate, a member pivoted to each spindle support and having an arm directly 110 engaging the spindle, and mechanism for operating each member about its pivot to longitudinally reciprocate the 115 spindles.
3. A cutter grinding machine comprising the combination of a rotary work support, a plurality of rotatable spindles each adapted to receive a grinding wheel thereon to 120 dress the work, a support for each spindle, means permitting adjustment of the spindle supports angularly relative to the work support, a member pivoted to each spindle support and having an arm directly engaging the spindle, mechanism for operating each member about its pivot to longitudinally reciprocate the 125 spindles, and means for automatically indexing the work support in timed relation to the spindle reciprocations.

4. A cutter grinding machine comprising the combination of a bed plate, a rotary work support thereon, a rotatable spindle adapted to receive a grinding wheel thereon to dress the work, a support for the spindle adjustable circumferentially on the bed plate, a member pivoted to the spindle support and having an arm directly engaging the spindle, and mechanism including a circular rack connected with the pivoted member for operating the member about its pivot to longitudinally reciprocate the spindle.
5. A cutter grinding machine comprising the combination of a rotary work support, rotatable spindles adapted to receive grinding wheels thereon to dress the work upon its sides and periphery, pivoted means directly engaging each spindle, and mechanism for operating each of the said means about its pivot to reciprocate the spindles longitudinally.
6. A cutter grinding machine comprising the combination of a rotary work support, rotatable spindles adapted to receive grinding wheels thereon to dress the work upon its sides and periphery, pivoted means directly engaging each spindle, certain of said means being pivoted to the spindle supports, and mechanism for operating each of the said means about its pivot to reciprocate the spindles longitudinally.
7. A cutter grinding machine comprising the combination of a rotary work support, a rotatable spindle adapted to receive a grinding wheel thereon to dress the work, a drive shaft, a member operatively connected to and adapted to be reciprocated by the drive shaft, and pivoted means forming a direct operative engagement between the reciprocating member and the spindle whereby the spindle is reciprocated.
8. A cutter grinding machine comprising the combination of a rotary work support, a rotatable spindle adapted to receive a grinding wheel thereon to dress the work, a drive shaft, a circular rack operatively connected to and adapted to be reciprocated by the drive shaft, and pivoted means forming a direct operative engagement between the rack and the spindle whereby the spindle is reciprocated.
9. A cutter grinding machine comprising the combination of a rotary work support, a rotatable spindle adapted to receive a grinding wheel thereon to dress the work, a drive shaft, a rack reciprocated thereby, two arms adapted to rock on a common pivot, one of said arms engaging the rack, and oscillating means forming a direct operative engagement between the other arm and the spindle whereby the reciprocation of the rack is transmitted to reciprocate the spindle longitudinally.
10. A cutter grinding machine comprising the combination of a rotary work sup-
- port, a rotatable spindle adapted to receive a grinding wheel thereon to dress the work, a drive shaft, a rack reciprocated thereby, two arms adapted to rock on a common pivot, one of said arms engaging the rack, a pivoted member, two arms extending from each pivoted member, one of said arms operatively engaging the spindle, and the other arm thereof operatively engaging the second arm on the common pivot whereby the reciprocation of the rack is transmitted to reciprocate the spindle longitudinally.
11. A cutter grinding machine comprising the combination of a rotary work support, an adjustably mounted rotatable spindle adapted to receive a grinding wheel thereon to dress the work, a member pivoted to the spindle support, an arm operatively connected to the spindle and movably mounted on and carried by the member, and mechanism for operating the member about its pivot to reciprocate the spindle longitudinally.
12. A cutter grinding machine comprising the combination of a rotary work support, an adjustably mounted rotatable spindle adapted to receive a grinding wheel thereon to dress the work, a member pivoted to the spindle support, an arm operatively connected to the spindle and movably mounted on the member, and mechanism including an oscillatable lever operatively connected to the member for operating the member about its pivot to reciprocate the spindle longitudinally.
13. A cutter grinding machine comprising the combination of a rotary work support, an adjustably mounted rotatable spindle adapted to receive a grinding wheel thereon to dress the work, a member pivoted to the spindle support, an arm operatively connected to the spindle and movably mounted on the member, mechanism including an oscillatable lever operatively connected to the member for operating the member about its pivot to reciprocate the spindle longitudinally, a drive shaft, and means reciprocated thereby and operatively connected to the lever.
14. A cutter grinding machine comprising the combination of a rotary work support, an adjustably mounted spindle adapted to receive a grinding wheel thereon to dress the work, a member pivoted to the spindle support, an arm operatively connected to the spindle and movably mounted on the member, mechanism including an oscillatable lever operatively connected to the member for operating the member about its pivot to reciprocate the spindle longitudinally, a drive shaft, and a circular rack having toothed engagement with the oscillatable lever and adapted to be reciprocated by the drive shaft.
15. A cutter grinding machine comprising

- ing the combination of a bed plate, a rotary work support thereon, a rotatable spindle adjustable circumferentially on the bed plate and adapted to receive a grinding wheel thereon to dress the work, a drive shaft, a circular rack having the teeth thereon extending circumferentially thereabout operatively connected to and adapted to be reciprocated by the drive shaft, and means, including an element having a plurality of teeth thereon engaging the teeth on the rack, operatively connecting the spindle with the rack whereby the spindle is reciprocated.

16. A cutter grinding machine comprising the combination of a bed plate, a rotary work support thereon, a rotatable spindle adjustable circumferentially on the bed plate and adapted to receive a grinding wheel thereon to dress the work, a drive shaft, a circular rack having the teeth thereon extending circumferentially thereabout and adapted to be reciprocated by the drive shaft, and pivoted means, including a toothed sector engaging the teeth on the rack, operatively connecting the spindle with the circular rack whereby the spindle is reciprocated.

17. A cutter grinding machine comprising the combination of an adjustably mounted rotatable spindle adapted to receive a grinding wheel thereon, mechanism for reciprocating the spindle longitudinally, including a drive shaft, a circular rack connected thereto and adapted to be reciprocated thereby, two arms adapted to rock on a common pivot, one of said arms having a toothed sector engaging the rack, and a pivoted member, two arms thereon, one of the said arm engaging the rotatable spindle and the second arm thereon having engagement with the second arm on the common pivot whereby reciprocatory movement of the rack will be transmitted to the spindle.

18. A cutter grinding machine comprising the combination of a rotary work support, a rotatable spindle adjustable relative to the work support and adapted to receive a grinding wheel thereon to dress the work, pivoted means directly engaging each spindle to reciprocate the spindles longitudinally, and means to vary the length of spindle stroke.

19. A cutter grinding machine comprising the combination of a rotary work support, rotatable spindles adapted to receive grinding wheels thereon to dress the work upon its sides and periphery, means composed entirely of pivoted members to simultaneously longitudinally reciprocate the spindles by movement about such pivots, and means whereby the length of operative stroke of the spindles may be varied.

20. A cutter grinding machine comprising the combination of a rotary work support, a rotatable spindle adapted to receive a grinding wheel thereon to dress the work, a drive shaft, a circular rack having the teeth thereon extending circumferentially thereabout operatively connected to and adapted to be reciprocated by the drive shaft, and means directly engaging the spindle and pivoted to the spindle support to reciprocate the spindle longitudinally, mechanism for operating the said means about its pivot, and means whereby the length of stroke of the spindle may be varied.

21. A cutter grinding machine comprising the combination of a rotary work support, a rotatable spindle adapted to receive a grinding wheel thereon to dress the work, a drive shaft, a member operatively connected to and adapted to be reciprocated by the drive shaft, oscillating means forming an operative connection between the reciprocating member and the spindle whereby the spindle is reciprocated, and means including a spring housed in the reciprocated member whereby the length of operative stroke of the spindle may be varied.

22. A cutter grinding machine comprising the combination of a rotary work support, a rotatable spindle adapted to receive a grinding wheel thereon to dress the work, a drive shaft, operating means, including a rod and a spring housed on the rod by a circular rack, between the drive shaft and the spindle whereby the spindle is longitudinally reciprocated, and adjustable means operating against the normal action of the spring whereby the length of operative stroke of the spindle may be varied.

23. A cutter grinding machine comprising the combination of a rotary work support, a rotatable spindle adapted to receive a grinding wheel thereon to dress the work, a drive shaft, a circular hollow rack reciprocated thereby, two arms adapted to rock on a common pivot, one of said arms engaging the rack, the other arm having operative connection with the spindle whereby the reciprocation of the rack is transmitted to reciprocate the spindle longitudinally, and means including a spring housed in the hollow rack whereby the length of operative stroke of the spindle may be varied.

24. A cutter grinding machine comprising the combination of a rotatable spindle adapted to receive a grinding wheel thereon, mechanism for reciprocating the spindle longitudinally including a drive shaft, a member resiliently connected to the drive shaft and adapted to be reciprocated thereby, a pivoted element, a plurality of arms on the element, one of said arms engaging the member and a second arm on the pivoted element having operative connection with the spindle whereby reciprocation of the member will transmit longitudinal reciprocatory movement to the spindle, and an adjustable means mounted to engage one of the said arms to limit the stroke of reciprocation.

25. A cutter grinding machine comprising the combination of a rotatable spindle adapted to receive a grinding wheel thereon, mechanism for reciprocating the spindle longitudinally including a drive shaft, a rod connected thereto and adapted to be reciprocated thereby, a circular rack resiliently mounted on the rod, a pivoted element, a plurality of arms on the element, one of 10 said arms being in toothed engagement with the rack and a second arm on the pivoted element having operative connection with the spindle whereby reciprocation of the rack will transmit longitudinal reciprocatory movement to the spindle, and an adjustable 15 means mounted to engage one of the said arms to limit the stroke of reciprocation.

In testimony whereof, I hereto affix my signature.

JOHN J. THACHER.
